(57) CLAIM

We claim the ornamental design for a bottle, substantially as shown and described.

DESCRIPTION

FIG. 1 is a top right isometric view of a bottle.

FIG. 2 is a bottom rear isometric view of the bottle of FIG. 1.

FIG. 3 is a front elevation view of the bottle of FIG. 1.

FIG. 4 is a rear elevation view of the bottle of FIG. 1.

FIG. 5 is a left side elevation view of the bottle of FIG. 1.

FIG. 6 is a right side elevation view of the bottle of FIG. 1.

FIG. 7 is a top plan view of the bottle of FIG. 1; and,

FIG. 8 is a bottom plan view of the bottle of FIG. 1.

The broken lines, which define the bounds of the claimed design, form no part of the claimed design.

1 Claim, 4 Drawing Sheets
